UNITED STATES PATENT OFFICE

114,341

DESIGN FOR AN AUTOMOBILE FENDER SHIELD OR SIMILAR ARTICLE

Donald Howard Mills, Detroit, Mich., assignor to
Houdaille-Hershey Corporation, Detroit, Mich.,
a corporation of Michigan

Application December 30, 1938, Serial No. 82,076

Term of patent 7 years

To all whom it may concern:

Be it known that I, Donald Howard Mills, a citizen of the United States and a resident of the city of Detroit, in the county of Wayne and State of Michigan, have invented a new, original, and ornamental Design for an Automobile Fender Shield or Similar Article, of which the following is a specification, reference being had to the accompanying drawing, forming a part thereof.

On the drawing:

Figure 1 is an elevational view of the automobile fender shield showing my new design, and showing a fender in dotted outline.

Figure 2 is a top plan view thereof.

I claim:

The ornamental design for an automobile fender shield or similar article, as shown.

DONALD HOWARD MILLS.
